UNITED STATES PATENT OFFICE

2,460,614

STRAINER

Myron J. Zimmer, Wood Dale, Ill., assignor to
Ekee Products Company, Chicago, Ill., a corpora-
tion of Illinois.

Application December 5, 1945, Serial No. 632,965

4 Claims. (Cl. 210—161)

1

This invention relates to new and useful improvements in the construction and assembly of a strainer wherein the peripheral edge of a bowl shaped filtering element of wire screening or fabric is attached to a rigid reinforcing frame or rim member.

One of the essential objects of the present invention is to provide a strainer of this type capable of being removably secured to a reinforcing rim member whereby the strainer may be dismantled to facilitate cleaning as well as to accommodate the substitution of filter elements of different character.

Another object is to provide a strainer of this type that is simple in construction and economical to manufacture.

With the above and other objects in view, as will be apparent, this invention consists in the construction, combination, and arrangement of parts, all as hereinafter more fully described, claimed and illustrated in the accompanying drawing, wherein:

Fig. 1 is a top plan view of a strainer embodying the features of this invention.

Fig. 2 is a side elevational view thereof.

Fig. 3 is an enlarged fragmentary cross-sectional view taken on line 3—3 of Fig. 1.

Reference being had more particularly to the drawing 10 represents a strainer body member of wire screen material in the shape of a bowl or cup and 11 indicates a continuous flange projecting laterally outwardly from the upper periphery of the body 10.

As shown in Fig. 3 the reinforced rim portion comprises separately formed members 12 and 14, each preferably made of a hardenable plastic material such as polystyrene, tenite or the like. Rim member 12 is provided with a continuous seat 15 with which the upper surface of the strainer flange 11 is engaged. Formed integrally with and extending downwardly from the inner limits of said seat 15 is a continuous inner wall 16 which presents an outwardly facing surface 17 with which the inner surface of the upper side wall portion of the strainer body 10 is engaged. A continuous outer wall 18 formed integrally with and extending downwardly from the seat 15 presents an inner face so spaced from the face 17 of the wall 16 as to surround the outer peripheral limits of the flange 11 with sufficient clearance to avoid the necessity of distorting the flange 11 when the same is moved inwardly of the walls 16 and 18 pending engagement with the seat 15.

The form and size of the second rim member 14 is such that it will fit between the walls 16 and

18 of the first rim member to impinge against the flange 11 and upper marginal portion of the strainer body 10, thereby securely clamping or holding said flange 11 and upper marginal portion 5 of the strainer body 10 in engagement with the seat 15 and face 17 of the wall 16. The inwardly facing wall 18 of rim member 12 is offset inwardly as at 19 to provide a relatively narrow upwardly facing shoulder 20 in downwardly spaced relation 10 to the seat 15 with which a downwardly facing shoulder projecting outwardly from the rim member 14 is engaged to prevent casual displacement or removal of the rim member 14 from its operative position between the walls 16 and 18 of the other rim member. The shoulder 20 is adapted to yield radially under pressure to accommodate movement of the shoulder on the rim member 14 past the inwardly offset portion 19 of the rim member 12 pending relative movement 15 of the rim members into a position of interengagement at said shoulders, due to the inherent resilient qualities of the rim members 12 and 14. Accordingly, while the rim members cooperate to set up a gripping engagement with the portions of the strainer located therebetween in a manner to prevent casual displacement or removal thereof, the members are yieldable under pressure applied at the inner bottom portion of the strainer bowl 10 to separate sufficiently to 20 permit intentional removal of the strainer and the rim member 14 when it is desired to replace the strainer with a new or different strainer.

As shown in Fig. 3, the bottom surface 21 of the rim member 14 and the bottom edge 22 of the wall 18 of the rim member 12 preferably occupy coplanar positions when the rim members 12 and 14 are in operative engagement, whereby the undersurface of the rim as well as other exposed surfaces thereof are free of pockets or 25 depressions susceptible to trapping dirt and other objectionable matter when in use.

As shown in the drawings, a laterally extending handle may be formed integrally with the rim member 12. Although a certain form of the 30 present invention has been shown and described by way of illustration it will be understood that it may be constructed in still other embodiments coming within the scope of the annexed claims.

What is claimed is:

1. In a strainer, a wire mesh bowl having an integral flange surrounding and extending laterally outwardly from its upper edge, a continuous member having a seat with which the upper surface of said flange is engaged, a continuous inner wall integral with and extending down-

wardly from the inner limits of said seat with which the inner surface of the upper side wall portion of the bowl is engaged, a continuous outer wall integral with and extending downwardly from said seat in spaced encircling relation to said inner wall and having an inwardly offset lower portion on its inner surface providing an upwardly facing seat between the upper and lower limits thereof, a second rim member insertable under tension into a final position between said inner and outer walls of the first rim member so as to bear upon the surfaces of said flange and said upper side wall portion of the bowl opposite to the surfaces thereof in engagement with the seat and inner wall of said first 15 rim member, said second rim member having a downwardly facing shoulder with which said shoulder on the outer wall of the first rim member cooperates to detachably lock said rim members against unintentional separation.

2. A strainer as described in claim 1 wherein the lower face of the second rim member and the

lower edge of the outer wall of the first rim member are substantially coplanar.

3. A strainer as described in claim 1 wherein said rim members are formed of hardenable plastic material.

4. A strainer as described in claim 1 wherein a laterally extending handle is formed integrally with said first named rim member.
